We claim the ornamental design for a rangefinder display device, as shown and described.

DESCRIPTION

FIG. 1 is a front view of a first embodiment of the rangefinder display device.

FIG. 2 is a perspective rear view of the first embodiment of the rangefinder display device in unclaimed environment.

FIG. 3 is another perspective front view of the first embodiment of the rangefinder display device in unclaimed environment; and,

FIG. 4 is a front view of a second embodiment of the rangefinder display device.

The broken lines within the circular solid line perimeter depict portions of the rangefinder display device that form no part of the claimed design. All other areas and broken lines outside of the solid line perimeter shown in FIGS. 2 and 3 depict environmental subject matter that forms no part of the claimed design.
